(57) **CLAIM**

The ornamental design for the leveling device, as shown and described.

DESCRIPTION

FIG. 1 is a top, front perspective view of a leveling device in accordance with our invention;

FIG. 2 is a front view of the leveling device of FIG. 1;

FIG. 3 is a rear view of the leveling device of FIG. 1;

FIG. 4 is a left side view of the leveling device of FIG. 1;

FIG. 5 is a right side view of the leveling device of FIG. 1;

FIG. 6 is a top view of the leveling device of FIG. 1; and,

FIG. 7 is a bottom view of the leveling device of FIG. 1.

The broken lines of the leveling device in FIGS. 1-7 are illustrative of portions of the leveling device that form no part of the claimed design.
